HYDRAULIC LOG-BARKER HAVING KERF-CUTTING AND BARK-REMOVING JETS

Robert Edward Burton, Willits, Calif.

Application October 17, 1950, Serial No. 190,549

2 Claims. (Cl. 144—208)

1

This invention relates to a method for debarking logs by hydraulic means, and to apparatus for carrying out the same.

In commercial lumbering operations the debarking of logs is accomplished in one of three ways; either by hand, by mechanical means or hydraulically. At the present time a considerable portion of all debarking is accomplished by hand labor. While the hand operation has the advantage of producing a good product and requiring almost no capital investment, it has the disadvantage of being expensive and tedious. Mechanical debarking is accomplished either by beating the bark to loosen it from the wood portion, or by cutting the bark off such as by shaving it in a large lathe. Both of these methods have the disadvantage of requiring substantially large capital investments in the machinery involved and of either producing a poor product or of being wasteful of the wood.

Hydraulic debarking methods making use of a jet of water, have in the past included one of three methods involving either eroding of the bark, beating of the bark, or blasting and disintegration of the bark. Any one or combination of these methods involves serious disadvantages. The method which involves an eroding action to wash the bark away in small pieces, requires comparatively low water pressures having a maximum of from 300 to 400 pounds per square inch. The eroding action takes place at a relatively slow rate and uses large volumes of water. Therefore this process has a low efficiency and economy and is generally unsuitable. The mechanical beating operation employing a plurality of whirling chains has been simulated in the hydraulic field by the employment of large volumes of water in the 600 to 1400 pounds per square inch range. In this method the force of the water is used to beat and loosen the bark from the wood portion of the log. This method has the disadvantage of requiring relatively large volumes of water at a high power cost as well as the inherent disadvantage of all beating processes whether mechanical or hydraulic in that when the bark is spongy, fibrous or soft its corresponding shock-absorbing characteristic results in further lowering of the efficiency.

The disintegration or blasting method also operates in the 600 to 1000 pounds per square inch range and operates upon the principle of concentrating upon one small area of the bark at a time, the object being to direct a considerable volume of water in a localized area to cause disintegration and blasting away of the bark in that

2

local area. This method also has the disadvantage of requiring a considerably large volume of water and operates with a relatively high power consumption. In general, therefore, all hydraulic methods of debarking which have been known before my invention have had the inherent disadvantage of very low efficiency and have been wasteful of both water and power.

It is an object of my invention to provide a method and apparatus for debarking logs which will overcome the faults of prior hydraulic debarking as set forth above.

Another object of my invention is to provide a method and apparatus for debarking logs which will require a relatively low volume of water in its operation.

Another object of my invention is to provide a method and apparatus for debarking logs which is simple both to install and operate and which will require a substantially lower capital expenditure than that required for those methods employing any of the methods outlined above.

A further object of my invention is to provide a method and apparatus for debarking logs which is rapid, efficient and economical in operation.

Additional objects and features of my invention will appear from the following description in which the preferred embodiments have been set forth in detail in conjunction with the accompanying drawings.

Referring to the drawings:

Figure 1 is an end elevational view illustrating one form of apparatus for carrying out my invention.

Figure 2 is a plan view of the apparatus shown in Figure 1.

Figure 3 is a fragmentary elevation of the bark-removing jets, as seen from the left end of Figure 1.

Figure 4 is a fragmentary elevation similar to Figure 3, but shows apparatus employing another embodiment of my invention.

Figure 5 is a fragmentary end view showing the embodiment of my invention as shown in Figure 4.

In general my invention utilizes the combined effect of at least two hydraulic jets, one which is a leading jet which cuts through the bark, followed by a peeling jet or jets which serve to peel the cut bark from the wood portion of the log. Both the cutting action and the peeling action are accomplished through the use of relatively low volumes of water in comparison to previous hydraulic methods.

A suitable apparatus for carrying out the

method of my invention is shown in Figures 1 and 2. While any suitable means may be used for holding and rotating the log 10 during debarking operations, I have shown in Figures 1 and 2 a series of rollers 11 mounted in pairs connected on each side by a pair of common shafts 12. Chain or belt drives 13 connect each of the shafts together and to the common drive motor 14 through the sprockets or pulleys 15. I have shown each roller 11 provided with an outer tooth or serrated peripheral ring 16 to prevent slippage between the rollers and the log. Pillow blocks 17 serve to journal the rollers and their shafting to the foundation bed 18.

In order to facilitate the handling of logs so that they may be easily fed to the machine, I have provided the ramp or skid 19. For removing the log after its debarking operation has been completed suitable means such as the crescent-shaped lifting arms 20, rotatable about their pivot points 25 by the hydraulic piston means 21, may be employed.

As shown in the apparatus of Figures 1 and 2, a pair of high velocity hydraulic nozzles 22 and 23 are mounted adjacent the outer surface of the log and upon the support arm 24. Nozzle 22 directs a cutting jet which serves to cut through the bark to the wood portion of the log. Nozzle 23 directs a bark peeling jet which serves to remove the bark from the wood portion of the log subsequent to the cutting operation. As shown, nozzle 22 is positioned upon the support arm 24 so that the jet which it produces will be directed through the bark to the wood portion in a direction along a radius of the log. The nozzle 22 is connected to a flexible hose 26 of the type capable of withstanding substantially high fluid pressures, as for example water at a pressure of from 3000 to 5000 pounds per square inch. Hose 26 is in turn connected to hydraulic pump means capable of delivering a volume of water, for example, from 3 to 5 gallons per minute at pressures up to 5000 pounds per square inch.

As shown, nozzle 23 is mounted upon the support arm 24 so that the jet which it produces is directed into the groove or kerf made by the cutting jet. Nozzle 23 is adapted to produce a relatively high velocity compact jet when connected by flexible hose 27 to a suitable pump capable of delivering for example a volume of from 10 to 22 gallons per minute at a pressure of 1500 to 2000 pounds per square inch.

Support arm 24 is provided with a counterweight 29 and guard rail 30 and is pivotally and movably mounted by means which will be presently explained. By such mounting the support arm 24 is movable the entire length of the log as well as pivoted for vertical movement to permit the loading and unloading of logs from the apparatus as well as for adjustment to size and irregularities of the logs. Nozzles 22 and 23 are maintained at a constant distance from the surface of the log by suitable means such as a pair of small wheels 28. Wheels 28 are so mounted that their support axles may be turned for positioning about an extended radius of the log. By turning and positioning each of the wheels 28 to an angle not perpendicular to the longitudinal axis of the log the movable support arm 24 may be moved the length of the log as the log is rotated.

Support arm 24 should be mounted so that it is easily movable both along the length of the log and vertically away from the log by suitable means providing a steady mounting for the noz-

zles. I can provide suitable anchoring facilities by mounting the guide rail 31 parallel to the log upon a series of support columns 32. Carriage means 33 provides pivotal and movable support along rail 31 for the support arm 24. Carriage 33 can include two pairs of rollers 34 for engaging either side of the web of the rail 31. To support the carriage means I can provide a pair of rollers 36 to roll upon the head of the rail. Rollers 36 serve as a fulcrum for the arm 24 and permit the arm and attached nozzles to be raised and lowered from the horizontal to provide for irregularities in the diameter of the log, logs of various diameters, and for loading and unloading. Bumper stop 37 can be provided extending parallel to the length of the apparatus and positioned beneath counterweight 29 to prevent undue movement of the support arm 24 about its fulcrum.

Having thus described one form of the apparatus suitable for use with my invention I shall now describe the mode of operation of such apparatus and method of my invention. To permit the loading of a log, support arm may be moved to one end of the track as for example the extreme left hand portion of Figure 2, or it may be lifted upwardly as by having the operator walk to the right end as viewed in Figure 1. Once the log has been rolled from the skid upon the rollers the support arm may be moved to the beginning position, which, as viewed in Figure 2, is the extreme right hand portion as shown in that illustration. Rotation of the log is begun by starting motor 14. Due to the angle at which the axles of rollers 28 are set to the plane of the longitudinal axis of the log, rotation of the log will impart traversing movement of the support arm along the longitudinal length of the log to its opposite end.

Hydraulic pumps are started to supply water at suitable high pressures to each of the nozzles 22 and 23. The cutting jet which nozzle 22 produces is directed to impinge radially upon the surface of the log and the pressure supplied to the nozzle may be regulated to control the cutting action of the jet to cut through the bark to the wood portion of the log. This pressure may be of the order of from 3000 to 5000 p. s. i. at a flow rate of from 3-8 G. P. M. The purpose of the cutting jet is to form a cut or kerf extending to the wood portion but not into the wood portion. By rotating the log and simultaneously moving the support arm the length of the log a helicoidal cut is made through the bark from one end of the log to the other.

Following in the kerf made by the cutting jet the peeling jet produced by nozzle 23 is directed to break away and remove the cut bark from the wood portion of the log. Since the cutting jet has formed a groove through the bark to the wood portion, the peeling jet working in cooperation therewith is directed to that region of the log lying between the wood portion and the bark. This region is known as the cambial region and is composed of those tree cells normally in the process of adding to the growth of the wood portion. I have found that the peeling jet should be of a lesser velocity and pressure than the cutting jet but of greater volume to exert more force against the bark in order to loosen and lift the strips of cut bark from the wood portions of the log. This pressure may be of the order of from 1500 to 2000 p. s. i. at a rate of from 10 to 22 G. P. M.

I have schematically illustrated the combined

action of the two jets in Figure 3 of the drawings. As shown, the cutting jet first cuts through the bark 41 to the cambial region 42 but not into the wood portion 43 and produces the groove or kerf 44. The peeling jet is directed to impinge substantially at the base of this kerf, in order that its force may be directed beneath the bark through the cambium region 42 to peel and remove the bark from the wood portion 43. As shown, the peeling jet is preferably positioned at an angle of from 30 to 45° to the plane of the wood portion surface of the log to properly impinge upon the cambial region and to break through that section of the log which forms a bond between the bark and the wood portion. The action of the peeling jet is such that it not only removes the bark from the wood portion but serves to carry the removed bark sections away from the log and the working area of the apparatus.

Once peeling of the log has been completed the supporting arm 24 is moved out of the way to permit removal of the log from the apparatus. Removal of the debarked log may be effected by rotation of the crescent shaped arms 20 about their pivot points 25 through the action of the hydraulic pistons 21, thereby serving to lift and remove the log 10 from the rollers and to dump it into the receiving chute 38.

Apparatus for carrying out the method of my invention may be varied depending upon the characteristics of the wood encountered. For example, if the bark is so thick that it is impossible for the peeling jet to impinge upon the cambium layer at an angle to that area sufficient to effect peeling, as for example in the case where the angle of incidence of the peeling jet is of the order of from 60 to 90°, it may then be desirable to use the modification I have shown in Figures 4 and 5. As shown in Figures 4 and 5, a peeling jet 23' is positioned to strike the log in the interval between the cuts made by the cutting jet. The peeling jet in this modification is directed to strike tangentially to the cambial region and at right angles to the longitudinal axis of the log. As shown, the peeling jet 23' does not impinge upon the log in the groove formed by the cutting jet, but is spaced from the cutting jet in a direction along the longitudinal axis of the log opposite to the direction of movement of the two jets along the length of the log. This method has been found quite effective in removing relatively thick bark from the wood portions of logs when using for example pressures of from 3000 to 5000 pounds per square inch at a flow rate of from 3 to 5 gallons per minute for the cutting jet and pressures of from 1800 to 2500 pounds per square inch at a rate of flow of from 9 to 22 gallons per minute for the peeling jet. In certain instances, by an obvious modification of the apparatus described, I have found it desirable in order to effect more efficient debarking to use a plurality of peeling jets positioned in a direction longitudinally of the axis of the log and preceded by the cutting jet.

Specific examples using apparatus similar to that described in Figures 1 to 3 inclusive for carrying out the method of my invention are as follows:

(a) Water was supplied to the cutting jet at a pressure of 4000 pounds per square inch at a volume of 3 gallons per minute, a cutting nozzle having an inside diameter of $\frac{1}{2}$ of an inch with its delivery end carried by the supporting arm at a distance of about 3 inches from the sur-

face of the log. Water at a pressure of 1800 pounds per square inch at the rate of 9 gallons per minute was supplied to a peeling nozzle which also had an orifice diameter of $\frac{1}{2}$ of an inch. 5 The cutting jet was directed at an angle of 90° to the upper surface of the log and the peeling jet was directed at about a 45° angle to that surface and impinged in the cut made by the cutting jet. A log of what is known as second 10 growth California redwood (*Sequoia sempervirens*) having a length of 5 feet and a diameter inside the bark of 7 inches was completely peeled in 74 seconds. The peeling took place with the speed of rotation of the log at a rate of approximately 12 R. P. M. and with a speed of advance of the cutting and peeling jets sufficient to provide an interval of 4 inches between the spiral cuts.

(b) A log of Douglas fir having a diameter 20 inside the bark of 9 inches and a length of 5 feet was peeled in 58 seconds under the same conditions of pressure, rate of flow, and jet positioning as in Example a. The log was rotated at a speed of approximately 10 R. P. M. with an 25 advance of the jet sufficient to provide an interval of 3 to 6 inches between spiral cuts.

From the above examples it is apparent that the comparatively hard bark and wood of the Douglas fir were easily adaptable to this method 30 and in fact were peeled faster and somewhat more thoroughly than the redwood logs which have a fibrous soft bark. In each of the above examples the bark had already set, but I have found that my method and apparatus is equally 35 effective on sap peeling wood and that the semi-tight condition of the bark does not appreciably interfere with the efficiency of my method.

In general I have utilized the principle that 40 the pressure of a stream increases the velocity of the jet from a nozzle and since the kinetic energy of the jet is proportional to the square of the velocity of the jet, by doubling the jet's velocity the kinetic energy is increased four-fold. However by increasing the volume or rate of flow 45 through a nozzle, because energy is directly proportional to a change in mass, a doubling of the volume or rate of flow will merely double the kinetic energy of the jet. Therefore greater kinetic energy can be effected from the jet by 50 increasing its velocity. The disadvantage and offsetting factor of this is the fact that the jet tends to disperse at relatively high velocities. I have found that the jet breaks up very quickly at the low volume-high velocity combination. 55 Therefore in order to utilize the jet effectively I place the nozzle forming the jet as close as possible to the bark. I have found this distance to be of the order of from 1 to 3 inches for both the cutting jet and the peeling jet.

60 I have found it desirable to sometimes vary the distance longitudinally of the log between spiral cuts through the bark depending upon the tenacity with which the bark is fixed to the wood portion of the log. This interval can be varied by 65 changing the angle at which the rollers 28 are positioned to the longitudinal axis of the log or by use of a single ball caster in place of rollers and regulating the speed of advance of the supporting arm 24 and the jets through the use of a variable speed windlass or hydraulic piston means. In order that the wood portion of the log not be damaged by the debarking operation I have found it necessary to control the 70 depths of cut made by the cutting jet either by

decreasing the pressure supplied to its nozzle or by increasing the speed of rotation of the log.

In general my method and apparatus have the advantage of using very small quantities of water to accomplish the debarking operation which results in both a saving of water, which is a great advantage in many timber areas, as well as a considerable saving in power. The combined action of the two jets disclosed in my method results in peeling a spiral strip of bark from the log which in turn results in a faster operation as well as an improved product. In addition because of the small quantities of water used the entire operation is simplified and the capital required for its installation is greatly reduced. Because of the simple operation and the small quantities involved and because the effective length of the jets are very short the method avoids many of the inherent dangers to personnel present in the earlier hydraulic debarking operations.

I claim:

1. Apparatus for debarking logs comprising means for rotating the log about its longitudinal axis, means for producing and directing a hydraulic cutting jet in a direction substantially radially of the log, said cutting jet serving to cut

a kerf through the bark to the wood portion of the log, and means for producing and directing a peeling jet into said kerf to remove the bark from the log.

- 5 2. Apparatus as in claim 1 in which said jet producing means are commonly mounted upon means serving to cause relative movement between the jets and the log in a direction longitudinally of the log to thereby produce a helicoidal kerf by the action of the cutting jet.
